ELECTRICAL CONNECTOR

Wallace L. Knute, Del Mar, Calif., assignor to Ivac Corporation, San Diego, Calif.

Filed July 20, 1972, Ser. No. 273,391

Term of patent 14 years

Int. Cl. D13—03

U.S. Cl. D26—1 A

FIG. 1 is a front perspective view of the electrical connector showing my new design;

FIG. 2 is a left side elevational view thereof;

FIG. 3 is a rear elevational view thereof;

FIG. 4 is a bottom plan view thereof;

FIG. 5 is a front perspective view of an electrical connector showing a second embodiment of my new design;

FIG. 6 is a left side elevational view of FIG. 5;

FIG. 7 is a rear elevational view of FIG. 5; and

FIG. 8 is a bottom plan view of FIG. 5.

I claim:

The ornamental design for an electrical connector, as shown.
